UNITED STATES PATENT OFFICE.

CHESLEY DOM, OF CINCINNATI, OHIO, ASSIGNOR TO THE SAMUEL C. TATUM COMPANY,
OF CINCINNATI, OHIO, A CORPORATION OF OHIO.

TEMPORARY BINDER.

1,079,640.

Specification of Letters Patent. Patented Nov. 25, 1913.

Application filed October 23, 1911. Serial No. 656,089.

To all whom it may concern:

Be it known that I, CHESLEY DOM, a citizen of the United States, residing at Cincinnati, in the county of Hamilton and State 5 of Ohio, have invented certain new and useful Improvements in Temporary Binders, of which the following is a specification.

My invention relates to an improvement in temporary binders, preferably of that 10 type known as post-binders, comprising two cover members, with one provided with a series of vertically projecting posts with which the second cover member engages and is adapted to be locked in various positions 15 of adjustment.

The object of my invention is to provide a temporary binder, with a cover member thereof provided with locking instrumentalities, adapted to engage with the posts of 20 a second cover member and automatically lock in one direction of movement of the cover member upon said posts, with means for withdrawing the locking instrumentalities from their post engagement.

25 Another object of my invention is to provide a temporary binder with a removable cover plate, adapted to be supported and adjusted upon a series of posts, said cover plate provided with angularly disposed 30 wedge engaging surfaces adjacent to a post projecting through the same, with wedging means interposed between the posts and such cover plate engaging surface, for locking the cover plate to said post, with means 35 for releasing the wedge from its post engagement.

Another object of my invention is to provide a temporary binder with a cover member, a resilient wedge supporting member 40 slidable longitudinally thereon, and with the cover member provided with a transverse slot to receive the binder post, with means for locking said post within said slot against horizontal removal.

45 Another object of my invention is to provide a temporary binder with a cover member, a series of locking instrumentalities supported by said cover member, each adapted to engage a binder post, with means 50 for simultaneously actuating said locking instrumentalities, to release the same from their post engagement.

Another object of my invention is to provide a member of a temporary binder with 55 binder locking instrumentalities, each of the

locking instrumentalities being provided with a resilient post engaging arm, and means for simultaneously moving said arms to and from their post engaging positions, said means comprising a rotatable cam 60 adapted to engage cam and hook surfaces formed on said locking instrumentalities.

The features of the invention are more fully set forth in the description of the accompanying drawing, forming a part of 65 this specification, in which:—

Figure 1 is a top plan view of the removable cover of the binder, showing the rear portion thereof. Fig. 2 is a central vertical section through the same, illustrating 70 the posts of the second cover member projected through the same. Fig. 3 is a detailed bottom plan view of the casing and is contained locking instrumentalities for locking the removable cover member to the 75 posts. Fig. 4 is a view, similar to Fig. 3, but illustrating a modified form thereof.

1 represents the removable cover member of a post binder, adapted to be engaged with and slid upon the posts 2, 3, secured and 80 projected vertically from a second cover member, not shown. The post type of binder is well known in the art, comprising two cover members, with one having a series of vertically projected posts and the second engaging with said posts and with the posts adapted to receive the loose sheets and clamped between the cover members. It is common in such type of binders to provide two posts in the series with post-engaging 85 mechanism supported upon the removable cover member intermediate of the posts. The rear portion of the removable cover member is usually formed of a metallic plate to give strength and rigidity thereto 90 and covered with cloth, with the forward portion of the cover member hinged to the plate.

4 represents the plate of the removable cover member 1, provided with the transverse slots, adapted to receive the posts 2, 3, to permit the cover to be mounted thereon in a horizontal plane, and 5 represents notches formed at right angles thereto and at the terminal of the latter slots; said 100 notches are provided with the inclined surface 6, against which a wedge engages, to lock the cover member in any adjusted 105 position upon the posts. The angle of said surface is such as to have a locking effect 110

upon the wedging instrumentalities in an upward movement of the cover, directing the same toward the posts and releasing them on a downward movement. This enables the cover to be pressed on the paper to be bound and automatically locked in position.

5 7 represents a casing secured to the plate 4, for supporting and housing the cover locking instrumentalities. Said housing is likewise laterally slotted coincident with the plate slots to receive the posts. As two sets of locking instrumentalities are illustrated and provided, simultaneously operated and 10 of duplicate construction, for convenience I will only describe one of them.

15 8 represents a slide plate, slidably mounted within the casing 7, with its sides 9 bent at right angles to the base of plate 8, which 20 are provided with the notches 10, adapted to receive the lips 11, projected from the casing 7, for maintaining the plate within the casing and holding the same against displacement, which is quite a convenience in 25 the manufacture of the binders. The plate 8 is notched at the medial portion thereof, so as to straddle the post in one of its positions and lock the cover against removal in a horizontal plane, Fig. 3 showing the plate slid 30 to such position.

35 12 represents an elastic arm fixed to the plate and projected toward the post, with its free end bifurcated and supporting a roller 13, which is adapted to wedge between the inclined surface 6, of plate 4, and the post of the binder, as shown in Fig. 2.

40 The plate 8 has an edge, opposite from the elastic arm, provided with an irregular 45 surface 13^a adapted to be engaged by the hook-shaped end 15 of the oscillating plate 14, which in an arc of movement in one direction will move the slide toward its post, and in an opposite or reverse direction engage with the hook 16 of the plate 8, to draw the same toward the axis of plate 14. In moving the plate 8 away from the post, the roller 5, by reason of its elastic support 12, will be withdrawn from its intervening position between the post and inclined surface 6, and moved beyond any binding or engaging position with the post. This enables the follower or cover member to be conveniently moved upon the post or 50 posts in any direction.

55 17 represents a winged handle secured to the oscillating plate 14, for oscillating the same. Thus turning the handle in one direction, the oscillating plate will engage 60 the cam edge of the plate 8 and move the arm into its notch engaging position with the notch 5, of the plate 4, retaining the same in such position, which enables the same to be automatically wedged between 65 the post and surface 6, of the plate 4, in

an upward movement of the plate and released on any downward pressure thereof. The oscillating plate and cam formation of the plate 8 are formed so that the engaging edge or point of the oscillating plate 14, 70 will have moved slightly past its longitudinal central plane, for bringing the same to a dead center, so as to resist any rearward movement of the plate 8 which would accidentally release the locking instrumentalities. 75

80 In the modified form, illustrated in Fig. 4, the plate 8 and limb 12 are formed integral and stamped from a single strip of metal with its function and operation substantially the same as the two-part form shown in Fig. 3.

85 It is obvious, that equivalent means may be provided for shifting the locking limb 12 for simultaneously controlling a series of such limbs other than the particular cam action herewith illustrated, without departing from the features of my invention.

Having described my invention, I claim:—

1. In a temporary binder, a series of binder 90 posts, a cover member adjustable thereon, comprising a plate notched and provided with an inclined surface adjacent to each post, a wedge member adapted to engage between each post and adjacent inclined surface of the plate, locking the parts together in an upward movement of the plate and released in a downward movement thereof, and an elastic arm carrying said wedge member for moving said wedge member 95 toward and away from its post-engaging position.

2. In a temporary binder, a series of binder posts, a cover member slidable on said posts having an inclined abutment adjacent to each post, an elastic arm at its free end journaling a roller wedge, one arm for each post, with the wedge adapted to intervene between the post and abutment, and bind therewith, and means for moving said arm transversely to the plane of the post to displace the roller wedge from a post-binding position. 105

3. In a temporary binder, a series of binder posts, a cover member slidable thereon, a slide plate slidably mounted upon said cover member, a resilient wedge supporting arm on said slide plate, a wedge member mounted on said arm, adapted to engage a post of the series, means for slidably moving said slide plate to and from said post for withdrawing said wedge from its post engagement. 115

4. In a temporary binder, a series of binder posts, a cover member slidable thereon, provided with notches extended therein from one edge to receive the posts in a lateral movement of the cover member, a yielding member, one for each post, slidable on the cover member, adapted to engage and bind with a respective post, and unitarily pro- 125 130

vided with a rigid element to close the notch around the post.

5. In a temporary binder, a series of binder posts, a cover member slidable thereon, means for locking said cover to said posts in any adjusted position, comprising a resilient arm slidable within said cover member, with its free end provided with a wedge, adapted to engage said cover and posts and 10 resist upward movement of the cover upon the posts, means adapted to engage said arm, for sliding the same to move said wedge out of locking position.

6. In a temporary binder, a pair of binder posts, a cover member slidable thereon, comprising a plate having notches to receive said posts, a pair of slides mounted on said plate intermediate of said notches, each provided with a resilient wedge arm, adapted to 20 engage with a respective post and inclined surface formed in said plate, and means for simultaneously moving said slides in a direction opposite each other for withdrawing the wedge arms from their post engagement.

25 7. A binder of the nature disclosed, combining a base, an impaling post projecting therefrom, a follower having a notch extended from one edge thereof to receive the post, a resilient limb and a rigid limb unitarily movable upon the follower, the one respectively to bind with the post, and the second to close the notch, and an oscillating member engaging said unitary limb member to move the same toward and from their 35 functioning position.

8. A binder of the nature disclosed, combining a base, a pair of impaling posts projected therefrom, a follower notched to receive therethrough said posts, a pair of movable members, one for each post unitarily 40 combining a resilient element having a roller journaled thereon adapted to wedge between

a respective post and the follower to bind the same to resist movement of the follower on the post in one direction, and release in 45 a reverse movement, and a rigid element functioning to gap the notch, and a manually oscillated member on said follower having hook limbs adapted to engage and interlock with said movable members to simultaneously move the same. 50

9. A locking device, comprising a plate having a pair of openings, each adapted to receive a post and with an inclined surface spaced from the post, a pair of resilient 55 members movable on said plate, each journaling a roller adapted to wedge between one of said inclined surfaces and posts to bind the posts and plate against movement of the parts independently in one direction. 60

10. A binder of the nature disclosed, combining a base, a pair of impaling posts projected therefrom, a follower notched to receive therethrough said posts, a pair of movable members, a cover plate upon said follower forming a slide way for said movable members, each movable member unitarily combining a resilient element and a rigid element, the resilient element having a roller journaled thereon, adapted to wedge 70 between a respective post and follower to bind the parts in one direction of movement of the follower on the posts and automatically release in a reverse movement, the rigid element functioning to close the notch 75 entrance, and means for simultaneously moving said movable members in opposing directions toward and from the posts.

In testimony whereof, I have hereunto set my hand.

CHESLEY DOM.
